CLAIM

The ornamental design for a vacuum, as shown and described.

DESCRIPTION

FIG. 1 is a front, left perspective view of a vacuum according to the invention.

FIG. 2 is a top, rear, right side perspective view of the vacuum of FIG. 1.

FIG. 3 is a rear view of the vacuum of FIG. 1.

FIG. 4 is a front side view of the vacuum of FIG. 1.

FIG. 5 is a right side view of the vacuum of FIG. 1.

FIG. 6 is a left view of the vacuum of FIG. 1.

FIG. 7 is a top plan view of the vacuum of FIG. 1; and, FIG. 8 is a bottom plan view of the vacuum of FIG. 1.

The broken lines shown in the drawings depict portions of the vacuum that form no part of the claimed design.
